US00D812877S

(12) **United States Design Patent** (10) **Patent No.:** **US D812,877 S**
(45) **Date of Patent:** **** Mar. 20, 2018**

(54) **SHOE SOLE**

(71) Applicant: **NIKE, Inc.**, Beaverton, OR (US)

(72) Inventors: **Kenneth Link**, Portland, OR (US);
Scott Murdoch McLeod, Portland, OR (US); **Ronald W. Wright**, Vancouver, WA (US)

(73) Assignee: **NIKE, Inc.**, Beaverton, OR (US)

(**) Term: **15 Years**

(21) Appl. No.: **29/608,439**

(22) Filed: **Jun. 21, 2017**

Related U.S. Application Data

(63) Continuation of application No. 29/564,524, filed on May 13, 2016.

CLAIM

The ornamental design for a shoe sole, as shown and described.

DESCRIPTION

FIG. 1 is a front-bottom perspective view of a shoe sole showing our new design;

FIG. 2 is a bottom view thereof;

FIG. 3 is a rear-bottom perspective view thereof;

FIG. 4 is a front-top perspective view of an alternative embodiment of a shoe sole showing our new design;

FIG. 5 is a top view thereof; and,

FIG. 6 is a rear-top perspective view thereof.

(Continued)

The broken lines showing the remainder of the shoe represent unclaimed subject matter and form no part of the claimed design.

1 Claim, 6 Drawing Sheets
